COMBINED LIPSTICK AND FLASHLIGHT

James J. Forlenza, New York, N. Y.

Application July 21, 1947, Serial No. 762,468

5 Claims. (Cl. 240—6.4)

1

This invention relates to new and useful improvements in self-illuminable lipstick applicators.

Among the objects of the invention are to provide a compact and practicable lipstick container and applicator having an improved illuminating means; to provide an attractive and relatively inexpensive container body; to provide a manually actuatable illumination control means of advantageous type, preferably one including a turn button at the bottom of the container; to provide a general assemblage of sheet metal or strip metal parts and parts of insulation material adapted for economical fabrication and interconnection, thereby to simplify the structural elements of the electrical circuit between a battery in the container, a light bulb adjacent the upper end of the lipstick and said turn button or other illumination control means; and to provide other improvements which will be referred to or become apparent hereinafter.

A feature of the invention is the provision of an illuminating light source, as the electric bulb aforesaid, which is so inclined from the vertical, or so associated with a reflector inclined from the vertical, that the lipstick-application illuminating light beam is directed toward the end of the lipstick during use of the latter.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of an embodiment of the invention as now favored, with the top lid removed.

Fig. 2, on an enlarged scale, is a vertical longitudinal section, taken on the line 2—2 of Fig. 1, but with the top lid in position.

Fig. 3 is a perspective view of an interior part constituting a cylindrical slideway for endwise advance of the lipstick from the container.

Fig. 4 is a transverse vertical section, taken on the line 4—4 of Fig. 2, with the top lid removed, and indicating in dot and dash the working head of the actuating turn button shown at the bottom of Fig. 2.

Fig. 5 is a horizontal section, taken on the line 5—5 of Fig. 3.

Fig. 6 is a fragmentary perspective view, looking toward the inside of the wall of the container

2

shown at the right in Fig. 2, this view showing the battery in dot and dash.

Fig. 7 is a top plan view of the bottom lid, detached.

5 Fig. 8 is a fragmentary elevation showing certain elements as seen at the upper part of Fig. 2, but illustrating a modification.

Referring first in detail to Figs. 1-7, the container, marked as a whole 10, includes a main 10 body having end walls 11 and 12, side walls 13 and 14, and a top wall 15; the container all around the same being shouldered at 16 and 17 for friction-retained, but removable mounting of a top lid 18 and a bottom lid 19.

15 Fig. 1 near one end has a downbent cylindrical neck surrounding a lipstick projection opening, and near its other end has a down-formed recess 21 having an inclined flat bottom wall 22 apertured at 23. Within the aperture 23 is a light bulb socket 24 having a top flange 25 by means of which the socket is hung in place with its center line inclined from the vertical; said flange being soldered in position as indicated at 26. Mounted in the socket 24 there is a light bulb 27 having a base 28 and an end contact 29.

25 The lipstick 30 is endwise raisable and lowerable by a finger-piece 31 movable along a slot 32 formed in the end wall 11. The finger-piece 31 is carried by a cylindrical cup 33 endwise movable along a slideway 34 shaped as best shown in Figs. 3 and 5 to have side wings 35 with the latter providing between them a slot-like opening 36 to match the slot 32. The slideway 34 may thus be defined as substantially omega-shaped in 35 cross-section. The main cylindrical portion of the slideway 34 has indent tabs 37 at its bottom, and at higher and lower points along said portion opposite the opening 36 are struck-out tongues 38 (see Figs. 2-5).

40 Said tongues 38 are sent through and clinched up against the far side of an insulation block 39, by way of slots in the latter, as best indicated in Fig. 2. With the insulation block 39 thus attached to the slideway 34, and with the top of

45 the insulation block wedged up tightly into the inverted trough 40 below the top wall 15 between the neck 20 and the recess 21, the parts 34 and 39 are rigidly mounted in place by application of the rivets 41 passing through the holes 42 in the wings 35 of the slideway 34 to secure the slideway to the wall 11. Then the top of the main body of the slideway 34 engages against the bottom of the neck 20 in axial alignment therewith.

55 When the top lid 18 is removed, the lipstick 30

may be projected upward for use, by means of the finger-piece 31.

For then illuminating the light bulb 27, the following parts are provided.

A resilient strip 43 of conductive metal (Figs. 2 and 4) along its main length is riveted as at 44 to the insulation block 39. Above the insulation block 29 the strip 43 extends as an upwardly inclined leaf spring carrying a stud 45 for making good electrical contact with the end contact 29 of the light bulb 27. Below the insulation block 39 the strip 43 extends as a contact finger 46.

The end electrode 47 of the replaceable battery 48 is resiliently engaged by the over-curved end 49 of a leaf spring 50 of conductive metal, the other end of said spring upstanding as a second contact finger 51. The spring 50 is riveted as at 52 to an insulation block 53, which is itself riveted as at 54 within the bottom lid 19.

Since the side-wall electrode of the battery 48 is embraced within a conductive metal mounting clip 55 riveted as at 56 to the end wall 13 of the main body of the container 10, which main body is of conductive metal, the battery is always conductively connected to one terminal of the light bulb 27.

When, therefore, the contacts 46 and 51 are bridged, the light bulb will be placed in circuit with the battery, and emit illumination.

This bridging is effected by rotation of the turn button 57, the shank of which is extended through the bottom lid 19 and the insulation block 53. Said shank, above said block, has secured thereto by a cross-pin 58 a cap 59 of inverted cup shape and of insulation material. Across said cap above the upper end of the shank of the turn button, is a cross-pin 60 of conductive metal. Thus, with the turn button at the angular setting shown in Fig. 2, the contacts 44 and 51 are bridged. A quarter turn of the push button in either direction energizes the light bulb if previously deenergized, and deenergizes it if previously energized.

The battery 48 at its top abuts an L-shaped bracket 61, riveted at 62 to the wall 12, and at its bottom rests on a similar bracket 63 riveted at 64 to said wall. The battery is releasably held against the wall 12 by the clip 55.

It will be noted that the battery 48 is placed in the container with its end electrode 47 lowermost. This is advantageous, as it allows the turn button to be placed on the bottom lid 19, and shortens materially one of the circuit-sub-division elements additional to the main body of the container; while, at the same time, loose wires are eliminated.

To remove the battery, as for a replacement thereof, it is merely necessary to remove the bottom lid 19, and then, by prying against its electrode 47, swing the lower end of the battery toward the left in Fig. 2 until the battery bottom is clearly away from the bracket 63, and slide the battery out of the container. The manner of insertion of a replacement battery will be clear from what has just been said.

It will further be noted that the light bulb 27 is positioned to direct its light beam at an angle, for converging the beam and the working point of the lipstick when the latter is projected for use.

Referring to the modification of Fig. 8, this shows the same collection of parts as seen at the upper part of Fig. 2, similarly viewed; the only differences here being the following. Instead of the recess 21, a recess 65 is provided

which has a horizontal bottom, this apertured for suspending a light bulb socket like the socket 24 as the latter is suspended but with the top flange 66 of the socket horizontal. Thus the axis of the light bulb 67 is vertical. However, overlying the flange 66 is a reflector 68, soldered in place as at 69 so as to be held to the desired inclination; such reflector having an aperture (not shown) located for having passed therethrough the base of the light bulb for seating of the latter in the socket. The strip 70 corresponds to the strip 43, with the upper leaf spring portion thereof for engaging the light bulb base merely slightly shorter in length, and being somewhat differently resiliently biased, than in Fig. 2.

It is to be understood that the light bulb may be connected in the device in any suitable manner depending upon the size, shape and material of the combined lipstick and flashlight.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a lipstick applicator having a hollow metallic body formed with spaced end walls, an open bottom end and a top wall formed with an opening adjacent one end wall and having a metallic guideway mounted within the body on the one end wall in axial alignment with the opening and slidably supporting a lipstick for extension through the opening, a metallic lid closing the open bottom end of the body, a metallic clip mounted on the other end wall of the body for supporting a battery with its shell contact engaged by said clip and with its end contact directed toward said lid, a light bulb socket mounted in a recess formed in the top wall of the body adjacent the opening for supporting a light bulb with its shell contact threadedly engaging said socket and with its end contact extended into the body, a resilient strip mounted on and electrically insulated from the side of the metallic guideway adjacent said clip and having its top end bent to engage the end contact of a light bulb supported in said socket, an insulation block mounted on the inside face of said lid beneath said clip, a metallic spring secured intermediate of its ends to said insulation block and having one end bent to engage the end contact of a battery supported in said clip, said spring having its other end bent to extend substantially at right angles to said insulation block, said resilient strip having its bottom end extended parallel to but spaced from the said other end of said spring, and means for electrically connecting the said other end of said spring and the said bottom end of said resilient strip for completing an electrical circuit
2. In a lipstick applicator having a hollow metallic body formed with spaced end walls, an open bottom end and a top wall formed with an opening adjacent one end wall and having a metallic guideway mounted within the body on the one end wall in axial alignment with the opening and slidably supporting a lipstick for extension through the opening, a metallic lid

closing the open bottom end of the body, a metallic clip mounted on the other end wall of the body for supporting a battery with its shell contact engaged by said clip and with its end contact directed toward said lid, a light bulb socket mounted in a recess formed in the top wall of the body adjacent the opening for supporting a light bulb with its shell contact threadedly engaging said socket and with its end contact extended into the body, a resilient strip mounted on and electrically insulated from the side of the metallic guideway adjacent said clip and having its top end bent to engage the end contact of a light bulb supported in said socket, an insulation block mounted on the inside face of said lid beneath said clip, a metallic spring secured intermediate of its ends to said insulation block and having one end bent to engage the end contact of a battery supported in said clip, said spring having its other end bent to extend substantially at right angles to said insulation block, said resilient strip having its bottom end extended parallel to but spaced from the said other end of said spring, and means for electrically connecting the said other end of said spring and the said bottom end of said resilient strip for completing an electrical circuit from the end contact of a battery supported in said clip to the end contact of a light bulb supported in said socket, and a top lid for engagement over the top end of the body over the opening and said recess.

3. In a lipstick applicator having a hollow metallic body formed with spaced end walls, an open bottom end and a top wall formed with an opening adjacent one end wall and having a metallic guideway mounted within the body on the one end wall in axial alignment with the opening and slidably supporting a lipstick for extension through the opening, a metallic lid closing the open bottom end of the body, a metallic clip mounted on the other end wall of the body for supporting a battery with its shell contact engaged by said clip and with its end contact directed toward said lid, a light bulb socket mounted in a recess formed in the top wall of the body adjacent the opening for supporting a light bulb with its shell contact threadedly engaging said socket and with its end contact extended into the body, a resilient strip mounted on and electrically insulated from the side of the metallic guideway adjacent said clip and having its top end bent to engage the end contact of a light bulb supported in said socket, an insulation block mounted on the inside face of said lid beneath said clip, a metallic spring secured intermediate of its ends to said insulation block and having one end bent to engage the end contact of a battery supported in said clip, said spring having its other end bent to extend substantially at right angles to said insulation block, said resilient strip having its bottom end extended parallel to but spaced from the said other end of said spring, and means for electrically connecting the said other end of said spring and the said bottom end of said resilient strip for completing an electrical circuit from the end contact of a battery supported in said clip to the end contact of a light bulb supported in said socket, and an insulation block mounted on the side of the metallic guideway adjacent said clip, said resilient strip being mounted on said latter-mentioned insulation block.

4. In a lipstick applicator having a hollow metallic body formed with spaced end walls, an open bottom end and a top wall formed with an

opening adjacent one end wall and having a metallic guideway mounted within the body on the one end wall in axial alignment with the opening and slidably supporting a lipstick for extension through the opening, a metallic lid closing the open bottom end of the body, a metallic clip mounted on the other end wall of the body for supporting a battery with its shell contact engaged by said clip and with its end contact directed toward said lid, a light bulb socket mounted in a recess formed in the top wall of the body adjacent the opening for supporting a light bulb with its shell contact threadedly engaging said socket and with its end contact extended into the body, a resilient strip mounted on and electrically insulated from the side of the metallic guideway adjacent said clip and having its top end bent to engage the end contact of a light bulb supported in said socket, an insulation block mounted on the inside face of said lid beneath said clip, a metallic spring secured intermediate of its ends to said insulation block and having one end bent to engage the end contact of a battery supported in said clip, said spring having its other end bent to extend substantially at right angles to said insulation block, said resilient strip having its bottom end extended parallel to but spaced from the said other end of said spring, and means for electrically connecting the said other end of said spring and the said bottom end of said resilient strip for completing an electrical circuit from the end contact of a battery supported in said clip to the end contact of a light bulb supported in said socket, said means comprising a shank rotatively mounted through said insulation block and said lid, a cap of insulation material mounted on the inner end of said shank and disposed between the adjacent faces of the bottom end of said resilient strip and the said other end of said spring, and a cross pin mounted diametrically through said cap and having its ends exposed at opposite sides of said cap to make contact with the bottom end of said resilient strip and the said other end of said spring when said shank is turned to a position in which said cross pin is at right angles between the adjacent faces of the said bottom end and the said other end.

5. In a lipstick applicator having a hollow metallic body formed with spaced end walls, an open bottom end and a top wall formed with an opening adjacent one end wall and having a metallic guideway mounted within the body on the one end wall in axial alignment with the opening and slidably supporting a lipstick for extension through the opening, a metallic lid closing the open bottom end of the body, a metallic clip mounted on the other end wall of the body for supporting a battery with its shell contact engaged by said clip and with its end contact directed toward said lid, a light bulb socket mounted in a recess formed in the top wall of the body adjacent the opening for supporting a light bulb with its shell contact threadedly engaging said socket and with its end contact extended into the body, a resilient strip mounted on and electrically insulated from the side of the metallic guideway adjacent said clip and having its top end bent to engage the end contact of a light bulb supported in said socket, an insulation block mounted on the inside face of said lid beneath said clip, a metallic spring secured intermediate of its ends to said insulation block and having one end bent to engage the end contact of a battery supported in said clip, said

said bottom end and the said other end, and a knob mounted on the outer end of said shank beneath said lid to be manually gripped for turning said shank.
